UNITED STATES PATENT OFFICE.

CLINTON L. WALKER, OF PIEDMONT, CALIFORNIA.

METHOD OF COUNTERBALANCING ENGINE MAIN SHAFTS.

Application filed February 4, 1924. Serial No. 690,682.

To all whom it may concern:

Be it known that I, CLINTON L. WALKER, a citizen of the United States, residing at Piedmont, county of Alameda, and State of

5 California, have invented new and useful Improvements in Methods of Counterbalancing Engine Main Shafts, of which the following is a specification.

This invention relates to engine main 10 shafts having a multiplicity of cranks or eccentrics, and more particularly to a method of counterbalancing the same.

Much consideration has been given of late 15 to the unbalanced forces inherent or developed in crank shafts used in high-speed internal combustion engines. The usual method employed when applying and positioning counterweights is to place a weight equal and opposite to each part or member 20 to be counterbalanced.

This method is fairly satisfactory where 25 the cranks at one side of the central transverse axis of the shaft are symmetrically arranged and in the same angular phase on opposite sides of the central transverse plane. Where the cranks or throws of a shaft are not so arranged, the application 30 of counterweights presents a different problem, and this problem is more complicated where space is not available for a counterweight opposite each crank or throw to be balanced.

In and by the present invention I provide 35 a method of counterbalancing an engine main shaft of the type wherein the throws or cranks at one side of the central transverse axis are not symmetrically arranged with respect to the cranks or throws at the opposite side. The object of the invention 40 is to generally improve and simplify the counterbalancing of a crank shaft of the type mentioned. A further object is to provide a method of counterbalancing crank shafts which will permit the use of a single 45 weight to counterbalance a number of cranks or throws, or which permits division of a single counterweight into a number of smaller weights placed at convenient points longitudinally of the shaft.

50 This system of counter-balancing permits a wider range of design than where both halves of the shaft are symmetrically arranged, and in the same angular phase on opposite sides of the central transverse plane. In other words, the shaft may be 55 designed to give a better balance of the in-

ertia forces of the reciprocating masses and to more nearly neutralize the bearing pressures caused by the centrifugal forces of the rotating masses.

60

For the purpose of clearly describing and illustrating the invention, reference will be made to the accompanying drawings, in which—

Fig. 1 is a side elevation of a counter- 65 balanced shaft employing eccentrics.

Fig. 2 is an end view thereof.

Fig. 3 is a side elevation of an ordinary 70 four-throw crank shaft counterbalance by my method.

70

Fig. 4 is an end view of Fig. 3.

By referring to Figs. 1 and 2, it will be noted that a main shaft is illustrated which employs eccentrics as a substitute for the common or ordinary crank throws; this type of shaft being illustrated by preference as it has heretofore been considered one of the most difficult types of shaft to counterbalance in view of the fact that equal and opposite counterweights cannot be employed. 80

The shaft illustrated is provided with three main bearings as illustrated at L, M and N, the bearing indicated at L being the central main bearing, and the bearings indicated at M and N the end bearings. 85 The eccentrics which are employed as a substitute for the usual crank throws and pins are indicated at A, B, C and D. These eccentrics are in this particular instance positioned 90° apart; that is, the eccentrics A and B are positioned 90° apart, the eccentrics B and C 180° apart, and the eccentrics C and D 90° apart. The eccentrics A and D are therefore opposed to each other and similarly the eccentrics B and C. This particular arrangement produces a static balance and also permits a better piston balance and equal distribution of the inertia forces exerted by the pistons.

In the present instance I employ two 100 counterweights such as illustrated at H and K. The counterweight K counter-balances the eccentrics C and D, and the counterweight H the eccentrics A and B. These counterweights are semi-circular and disk shape as illustrated in Fig. 2, and they are suitably secured to an annular disk forming 105 an integral part of the main shaft.

The method of positioning the counterweights and determining the weight thereof 110 consists in computing the centrifugal forces due to each member on the crank shaft that

runs out of balance by employing the usual formula that centrifugal force equals $.00034 WRN^2$, where W is the weight, R its radius of gyration, and N the number of revolutions.

- Eliminating the constants and considering one speed only, it is seen that the centrifugal force is directly proportional to the weight times the radius of gyration. Consider now 10 that the crank shaft is being held firmly by one end and the center main bearing, leaving half the shaft projecting as a cantilever. Measure the distance along the shaft from the center of the main center bearing to the 15 center of gravity of the eccentric B or other unbalanced weight or mass. Compute the centrifugal force due to the weight of B with its radius of gyration for any given number of revolutions per minute by the 20 use of the above formula. The bending moment around the central point O of this unbalanced force is the product of this force times its distance along the shaft to the central point O . Now measure the distance 25 from the center of the main bearing L or the point O to the second eccentric indicated at A , which is the next unbalanced weight or mass encountered, and compute its centrifugal force and bending moment around the 30 central point O in the same way as for eccentric B . This bending moment it will be noted acts in a radial plane at 90° to the plane of B . By the construction of a parallelogram of forces we can readily determine 35 the resultant of these two moments both as to magnitude and the angle of its radial plane of action. In like manner we would proceed with all of the remaining out of center masses taking each in turn to determine 40 its resultant with the resultant already found until a final resultant is found which represents the resultant bending moment of all of the out of center masses both as to magnitude and the angle of its radial 45 plane of action. The center of gravity of the counterweight H will lie on the opposite side of the shaft and in a continuation of the radial plane of the final resultant bending moment of all of the out of center masses. 50 The weight and position of H must be such that its centrifugal force multiplied by the distance of its center of gravity along the shaft to the central point O must be equal and opposite to the final resultant bending 55 moment of all of the out of center masses.

The position and weight of the counterbalance H is thus determined, but if it is desired to divide this weight into several weights for the purpose of conveniently placing the same along the shaft, it may be accomplished by placing the weights in the desired positions longitudinally along the shaft and in such radial planes and of such shapes and weights that their resultant bending moment shall be equal, opposite and

in the same radial plane as the resultant bending moment of all of the out of center masses and hence equivalent to the action of the single weight H . This rule can be applied to any shaft with the cranks or eccentricities set at any angle, and the same rule is followed for each half of the shaft. 70

For the purpose of illustrating the method of attaching the counterweights to an ordinary crank shaft, reference is made to Figs. 75 3 and 4. This shaft is identical in size and throw to the shaft shown in Figs. 1 and 2, and is similarly provided with three main supporting bearings as indicated at L' , M' and N' . Four cranks are also provided as 80 indicated at A' , B' , C' and D' , and four counterweights are employed as indicated at H' , K' , h and k , the idea of illustrating the four counterweights being that of showing the possibility of dividing one weight into 85 two or more.

To determine the position and the magnitude of the weights indicated at H' and h , the same rule is followed; that is, the shaft is considered as supported by the central 90 bearing and one end bearing, and the remainder of the shaft is considered as a cantilever. The distance from the central point O to each unbalanced weight is determined. For instance, the weights of the respective crank cheeks and pins are determined, as also their radii of gyration. The centrifugal force or pull exerted by each unbalanced member is thus determined and the bending moment exerted thereby with 100 relation to the central point O is similarly determined. By parallelograms of forces the resultant of all these bending moments can be determined by plotting the products of the weight times the radius of gyration, 105 times the distance to the center. The resultant will show in magnitude and in direction the total force to be counterbalanced, and will represent the product of the weight of the counterbalance times its radius of 110 gyration, times its distance longitudinally along the shaft to the center bearing; the weight being in this instance divided into two weights as shown at H' and h . It can thus be seen that dynamic balance is readily 115 obtained; that equal and opposite weights are not essential; that one or more counterweights may be employed to balance a number of smaller weights. Thus the cost of manufacture may be materially reduced and 120 the counterweights may be placed where the clearance in the crank case best permits.

The center of gravity of the counterweight H is on the line 1-1. This line falls within the angle produced by the center line 2-2 of 125 the throw A and line 3-3 which bisects the angle formed by throws A and B . Thus the center of gravity of the weight H which serves to counterbalance throws A and B does not coincide with the bisector line 3-3, 130

but inclines towards the line 2-2 which is the center line of the throw farthest from the point O or central transverse plane of the shaft.

5 While the present method permits any number of counterweights to be used and to be placed at any desired point longitudinally of the shaft, it is preferred to have one of the weights on each half of the shaft 10 positioned midway between the end crank and the next adjacent crank, such weight to be so proportioned that it will off-set any tendency on the part of the shaft to be deflected between the center bearing and the 15 end bearing. If the weights are positioned solely at the ends of the shaft, they will not oppose this tendency of the shaft to deflect between the end bearing and the center bearing, and in a high-speed shaft such deflection would cause serious vibration, increased 20 noise and consumption of power, and in extreme cases might rupture the shaft.

Having thus described my invention, what I claim and desire to secure by Letters 25 Patent is—

1. A method of counterbalancing an engine main shaft having four throws, with the throws set as follows: Throws 1 and 4 set at 180° apart; throws 2 and 3 set at 180° 30 to each other but at 90° to throws 1 and 4; which consists in treating each half of the shaft as a cantilever supported at the central transverse plane of the shaft, determining 35 the bending moment of the cantilever at the point of support produced by the centrifugal force of each throw multiplied by the distance from the central transverse plane of the shaft, and counteracting this bending moment by weights of such mass and 40 radius of mass center and distance from the central transverse plane of the shaft that their bending moment will be equal and opposite to that of the throws to be balanced. 45 2. A counterbalanced engine main shaft having four throws, with throws 1 and 4 set 180° apart and throws 2 and 3 set 180° apart but at 90° from throws 1 and 4, and counterbalancing weights for each half of the shaft, said weights being positioned 50 with respect to the throws to be balanced so that their center of gravity falls within

the angle produced by extending the center line of the outer throw and a line bisecting the angle of the two throws.

3. A counterbalanced engine main shaft 55 having four throws, with throws 1 and 4 set 180° apart and throws 2 and 3 set 180° apart, but at 90° from throws 1 and 4, and counterbalancing weights for each half of the shaft, which weights have a resultant 60 moment equal and opposite to the resultant moment of the off-center masses on the adjacent half of the shaft calculated by multiplying the mass by its radius of mass center by its distance from the central transverse 65 plane of the shaft, one of such weights on each half of the shaft being positioned midway between the end throw and the next adjacent throw, whereby to prevent deflection of the shaft between the center and end 70 thereof.

4. An engine main shaft having a plurality of throws at each side of the central transverse plane, which throws are not in mirror symmetry, and counterbalancing 75 weights for each half of the shaft having a resultant moment equal and opposite to the resultant moment of the off-center masses on the adjacent half of the shaft calculated by multiplying the mass by the radius of 80 mass center by the distance from the central transverse plane of the shaft, one of said counterbalancing weights on each half of the shaft being positioned midway between the end of the shaft and the central transverse plane thereof, and being of such mass as to offset the tendency of the shaft to be deflected at the central point of each half. 85

5. A counterbalanced engine main shaft having four throws, with throws 1 and 4 set 180° apart, and throws 2 and 3 set 180° apart but at 90° from throws 1 and 4, and a single counterbalancing weight positioned 90 between the two throws on each half of the shaft and having its center of gravity within the angle produced by extending the center line of the outer throw and a line bisecting the angle of the two throws, such weight 95 being effective to assist in counterbalancing the two adjacent throws.

CLINTON L. WALKER.
